EXCAVATING MACHINE

David L. Raymond, Dayton, and Harold H. Hoover, Cleveland, Ohio, assignors to The Cleveland Trencher Company, Cleveland, Ohio, a corporation of Ohio

Filed Mar. 23, 1959, Ser. No. 801,984

12 Claims. (Cl. 37—97)

This invention relates in general to improvements in trench excavating or ditching machines and more particularly to a ripper or cutter blade arrangement for the digging unit of a trenching machine, for enabling the latter to be effectively used and operated in the excavation of relatively hard materials, such as shale, sandstone, coral and the like.

Modern trenching machines generally comprise a compact mobile machine designed to go almost anywhere and to dig into most kinds of material. The machine includes a continuous or endless digging unit, consisting often times of a rotary wheel on the periphery of which are mounted a plurality of bucket elements which scoop up the material being excavated and move it to a discharge station on the machine, where it is handled generally by a power driven conveyor, or other suitable mechanism, to move the excavated material to the sides of the excavation. The aforementioned buckets generally are provided with a plurality of excavator or rooter teeth projecting outwardly and forwardly therefrom for digging into the material to be excavated and facilitating its removal by the buckets. The maximum efficiency of any excavating machine is reached when the greatest amount of material is dug in a unit of time.

The nature of the soil affects the efficiency of the machine and heretofore considerable difficulty was encountered when attempting to operate in or to excavate relatively hard material such as the aforementioned shale, coral or the like.

The present invention provides a scarifier or scoring blade arrangement for the digging unit of a trenching machine for slicing or ripping hard material to be excavated prior to its being engaged by the conventional excavator teeth of the moving buckets of the unit, to facilitate the removal of the material by the digging unit, and thus greatly increase the efficiency of the machine. In addition, the present arrangement improves the operating characteristics of the digging unit in hard material by helping to alleviate the "pounding" of the digging unit when operating in such hard material.

Accordingly, an object of the invention is to provide an excavating machine embodying an improved digging unit for effective use or operation in relatively hard material.

Another object of the invention is to provide a trenching machine of the latter type wherein the digger unit embodies conventional bucket and excavator tooth structure, in combination with a novel ripper or cutter blade arrangement for cutting or slicing the hard material prior to its engagement by the excavator teeth, and thus facilitate the removal of the material by the digging unit of the machine.

A further object of the invention is to provide a novel and uncomplicated ripper blade arrangement for use with the excavating buckets of the digging unit of a trenching machine, for greatly increasing the efficiency of the digging unit when operating in relatively hard material.

2

A still further object of the invention is to provide a ripper or cutter blade arrangement of the latter type for use with a wheel type trenching machine for greatly increasing the operating and service-life characteristics of the digging unit of the machine when operating in hard material, and aiding to eliminate "pounding" of the digging unit and resultant detrimental vibration of the machine proper.

Other features and advantages of the invention will be apparent from a consideration of the following description taken in conjunction with the accompanying drawings wherein:

Fig. 1 is a side elevation of an excavating machine embodying the instant invention.

Fig. 2 is a fragmentary, enlarged, side elevational view of one of the buckets of the digging unit of the excavating machine of Fig. 1.

Fig. 3 is a front elevational view taken generally from the right hand side of Fig. 2.

Fig. 4 is a front elevational view of the next adjacent bucket to that shown in Figs. 2 and 3 and taken in a counterclockwise direction with respect to the digging unit as illustrated in Fig. 1.

Fig. 5 is a front elevational view of the bucket next adjacent to that of Fig. 4 and taken in counterclockwise direction as viewed in Fig. 1.

Fig. 6 is an enlarged, side elevational view of one of the holder elements for the ripper blade arrangement of the instant invention with an associated ripper blade (shown in dot-dash lines) being mounted therein.

Fig. 7 is a top plan view of the holder element illustrated in Fig. 6.

Fig. 8 is a side elevational view of one embodiment of the novel ripper blade elements of the instant invention.

Fig. 9 is a top plan view of the ripper blade element illustrated in Fig. 8.

Fig. 10 is an end elevational view of another of the ripper blade elements utilized in the novel ripper blade arrangement of the instant invention wherein the blade element is bent so that when in mounted position on a bucket, the cutting portion thereof is disposed in a plane extending generally parallel to the plane of movement of the bucket, and as can be best understood from the right hand side of Figs. 4 and 5 of the drawings.

Fig. 11 is a fragmentary, enlarged, side elevational view of one of the buckets of a digging unit illustrating another embodiment of the ripper blade arrangement of the invention.

Fig. 12 is a fragmentary, front elevational view taken generally along the plane of line 12—12 of Fig. 11, looking in the direction of the arrows, but with parts of the bucket removed.

Fig. 13 is an enlarged, side elevational view of one of the holder elements for the ripper blade arrangement of Figs. 11 and 12, with an associated ripper blade (shown in dot-dash lines) being mounted therein.

Fig. 14 is a top plan view of the holder element illustrated in Fig. 13.

Fig. 15 is an enlarged side elevation of one of the ripper blade elements utilized in the Figs. 11 and 12 arrangement, as taken from the right hand side of Fig. 12.

Fig. 16 is a view generally similar to Fig. 12, but showing a further modification of the invention.

Referring again to the drawings and especially to Fig. 1 thereof, there is shown a trenching machine of the well known wheel type embodying the instant invention. Such a trenching or excavating machine broadly comprises a main frame 10 supported on suitable tractor treads 12, a main power plant or internal combustion engine 14 supported on the forward end of frame 10, mast structure 16 for supporting a vertically movable boom structure 18, an excavating wheel or unit 20 rotat-

ably mounted on boom 18 by means of wheel and frame arrangement 22 and 22a, and drivingly connected to the motor unit 14 of the machine by the chain and sprocket arrangement generally referred to by reference number 24, and a transversely extending discharge conveyor 26 which is adapted to receive material from the buckets 27 of digging unit 20 and then carrying it to either side of the machine. Boom structure 18 is pivotally mounted with respect to the mast structure 16, as at 28, for movement in a generally vertical plane, and may be raised and lowered on mast structure 16 as by means of cable and pulley systems 30 actuated by winding drums 32 and 34 mounted on the machine frame. It will be understood of course that other structural arrangements and systems could be utilized for controlling the movement of boom 18 and associated digging unit 20 without departing from the scope of the present invention.

The digging unit of the machine is adapted to rotate in the direction of the arrow Z in Fig. 1 so that the forward edge of the excavating buckets and associated rooter teeth will engage the material to be excavated, scoop it up and then carry it upwardly to discharge conveyor 26.

The excavating buckets 27 are of generally U-shaped configuration in front elevation with the leg portions 27a thereof secured as by means of fastener elements 36 to the respective sides of the wheel of the digging unit and having some suitable back-up means 37 such as in the form of a solid back wall or the spaced finger elements illustrated, for retaining the material dug, in the buckets until arrival at the unloading conveyor 26. A plurality of conventional generally flat rooter or excavating teeth 38 are secured to the exterior periphery of each bucket body by any suitable means, and extend generally diagonally forwardly from the leading or front edge thereof. In the embodiment illustrated, the rooter teeth are of the replaceable tip type, well known in the art.

The rooter teeth are positioned around the flared lip portion 39 of their respective buckets, in a predetermined number and manner, so that the teeth on each following bucket are spaced transversely from those on the adjacent buckets, whereby the teeth of a predetermined series of buckets substantially completely engage and excavate the total predetermined transverse width of the trench. In other words, in the embodiment of the invention illustrated, the buckets are illustrated in a series of three buckets designated by letters A, B, and C respectively, with the rooter teeth on bucket B, which follows bucket A, being generally disposed transversely of the rooter teeth on bucket A, and with rooter teeth on bucket C being disposed transversely of those on bucket B, to thereby provide a substantially clean cut trench or excavation for its total width. It will be understood of course that depending on the width and number of the rooter teeth, and the width of the buckets, the latter could be grouped in a different numerical series, to provide substantially complete engagement of the rooter teeth in one particular series with the complete width of the material to be excavated from a predetermined width of trench. The latter arrangement is known in the art and forms no particular inventive concept in the instant application.

In accordance with the invention, each bucket 27 is provided with a plurality of ripper blades 40 set edge-wise and mounted around the exterior of the respective buckets, for cutting or slicing into hard material prior to engagement of the material by the rooter teeth on the following bucket, to facilitate the digging of the material from the trench. Each of the ripper blades, in the embodiment illustrated, is supported in a holder element 42 (Figs. 6 and 7) which is mounted by any suitable means, such as welds 43 to the periphery of the bucket, and as shown in the Fig. 2 embodiment, generally intermediate the respective rooter teeth 38.

Each holder element, in the embodiment of the invention illustrated, is of fabricated construction comprising side walls 44, and front and rear walls 46 and 48 respectively (Figs. 6 and 7), defining there between a socket 50 for receiving therein a ripper blade 40. The front and rear walls have rearwardly and downwardly sloping inner surfaces 46a and 48a respectively adapted to engage the confronting end surfaces 52 of the ripper blade 40 and support the substantially upstanding blade in a generally diagonally and forwardly sloping position. The side walls 44 of the holder are provided with aligned openings 54 therein for receiving a pin element 56 extending through the side walls and through a complementary opening 58 in the base of the ripper blade 40 for holding the blade in assembled position in its socket. The pin 56 may be held in assembled position by a force fit or any other suitable means.

The ripper blades 40 are preferably formed of hardened steel or the like, and with the inner end surfaces 60 thereof, which are adapted for disposal in the holder elements, preferably so formed as to engage in surface-to-surface coaction with the confronting surface of the bucket when in assembled relation with the holder. The outer end surface 62 of the ripper blade in the Fig. 8 embodiment is formed to extend generally parallel to the bottom surface thereof and thus generally parallel to the exterior configuration of the lip portion 39 of the bucket, and are of generally parallelogram configuration in side elevation in the embodiment illustrated. The blade elements are formed so as to project generally beyond the path of movement of the associated rooter tooth on the respective bucket, and thus cut or slice into the hardened material being excavated a predetermined greater amount than do the rooter teeth, as may be readily seen in Fig. 1.

In the embodiment of the invention illustrated in Figs. 1 to 10, the ripper blades are positioned rearwardly of the forward edge 64 (Fig. 2) of the respective bucket, and inwardly of the outer ends of the associated rooter teeth, and thus give a substantially greater support for the buckets during the excavating operation, to aid in alleviating "pounding" of the digging unit when operating in the aforementioned hard material. As best shown in Figs. 3 and 10 of the drawings, the ripper blades 40 disposed along the side portions of the buckets, are bent intermediate their ends, a predetermined amount, as at 65, and above the opening 58 therethrough, so as to maintain the cutting portions thereof in planes generally parallel to the plane of movement of digging unit, to thereby aid in preventing inadvertent fracture of the blades, and providing a longer service life therefor. Thus the cutter blades 40 have a bi-planar configuration as opposed to the planar configuration of blades 40.

The ripper blades are preferably so positioned on their associated buckets so that they are generally aligned in a longitudinal direction with the rooter teeth on the following bucket, so that the rooter teeth on such following bucket always engage the hard material in the vicinity of where it has been cut or sliced into by the ripper blades on the preceding bucket. This can be best seen from Figs. 3 to 5 of the drawings. The ripper blades on bucket A are positioned so as to be generally longitudinally aligned with the rooter teeth 38 on following bucket B, as taken in a counterclockwise direction in Fig. 1, and the ripper blades on bucket B (Fig. 4) are disposed in general alignment with the rooter teeth on bucket C (Fig. 5), while the ripper blades on bucket C are generally aligned with the rooter teeth on the next following bucket A, the buckets and associated rooter teeth being assembled on the wheel of the digging unit as aforesaid in series of three's.

In operation, the trenching machine moves forwardly in the direction of the arrow X in Fig. 1, while the digging wheel rotates, with the ripper blades on for instance bucket A, slicing into the hard material, following which

the rooter teeth on following bucket B undercut such sliced or ripped material, and then the latter is scooped up by the buckets and moved to the discharge conveyor 26 where it is discharged to the sides of the excavation. Since the ripper blades are of relatively thin, hardened, plate-like material, they readily cut or score into the hard material to be excavated with relatively little resistance, and greatly expedite the digging of the trench. If the ripper blades become unduly worn after long service or inadvertently fracture in operation, they can be readily replaced by removal of the connecting pins 56 from their respective holders. Furthermore, such ripper blades do not interfere with the operation of the machine in softer soils and may be left in mounted position, if so desired, or the blades may be removed from the holders, with the latter being left on the buckets.

Referring now to Figs. 11 to 15, there is shown a modification of the invention. In this modification, the holder elements 70 are secured by any suitable means, such as welds, to the outer surface 71 of an arcuate-like elongated strap element 72, which in turn is mounted or secured by any suitable means, such as welding, to the periphery of the bucket, so that the under surface 73 of the strap element is disposed in confronting relation with the exterior of the bucket. The strap element 72 and attached holder elements 70 are mounted further rearwardly on the associated bucket as compared to the first embodiment of the invention and thus give even greater support to the digging unit when operating in hard material to alleviate "pounding" and associated vibration in the machine. Moreover the holder elements in this embodiment may include a bottom wall portion 74 which serves to reduce the length of the associated ripper blade 76 for a predetermined magnitude of projection above the associated rooter teeth 38 on the bucket. The front and rear wall portions 78 and 78a, of the Figs. 13 and 14 holder 70, are also recessed within the side wall portions 44, as opposed to the first described embodiment wherein the front and rear walls projected outwardly from the side walls thereof. The outer end surface 80 of the ripper blade in this embodiment is sloped downwardly in a rearward direction as compared to the inner end surface 80a thereof, to provide a sharper leading point 82 for the cutter blades when in mounted position on the rearward end of the associated bucket. As shown in Figs. 11 and 12, the holder elements 70 are mounted on associated strap 72 so as to be disposed in planes extending generally parallel to the plane of movement of the buckets and parallel to a vertical plane passing through the center of curvature of strap 72. Spacer elements 84 may be utilized to provide for the parallel plane relationship. As may be best seen in Fig. 11, the central or uppermost of the holder elements 70 are preferably spaced from the forward or leading edge 86 of the associated strap, while the lower or outermost holder elements disposed more along the sides of the bucket, are positioned substantially flush with such forward edge 86 of strap 72, to provide a longitudinally off-set arrangement. In all other respects, the Figs. 11 to 15 arrangement is generally similar to the first described embodiment of the invention.

It will be seen that such a unit arrangement of a mounting strap with the holder or socket elements 70 all secured thereto in one packaged sub-assembly, makes it much easier to apply or remove the ripper blades to or from the buckets.

Fig. 16 shows a further modification of the invention wherein the holder elements 70 are secured to the outer surface of a mounting strap 72 in generally radial extending fashion, rather than embodying spacer elements to position such holders in parallel plane relation with the plane of movement of the digging unit. The ripper blades utilized with the Figure 16 embodiment may be of the same type as illustrated in the Figs. 11 to 15

embodiment of the invention or may be of the bent type of ripper blade as illustrated in Fig. 10 of the first described embodiment of the invention whichever is deemed most desirable for the material to be excavated. 5 In any event, the Fig. 16 arrangement provides a unitary sub-assembly which can readily be mounted on or removed from a bucket and in a similar manner as afore-described in connection with the Figs. 11 to 15 embodiment.

10 A suitable material for the cutter blades of the invention has been found to be $\frac{3}{8}$ inch, 1060 to 1080 steel plate, heat treated to Rockwell, C, 50-55 hardness, but it will be understood of course that other suitable materials or other types of steels could be utilized.

15 While the scoring or scarifying blade arrangement of the invention has been illustrated in the drawings as being applied to the buckets, it will be understood that such structure could be applied to the digging unit intermediate the buckets, without departing from the scope 20 of the invention, such as by mounting a scoring blade arrangement of proper size and as for instance the type illustrated in Fig. 12 of the drawings, directly on the excavating wheel 20 intermediate the bucket members. It will also be understood that while the buckets have 25 been illustrated as being of an arcuate or rounded design, any other conventional configuration of bucket could also be used, such as a square design, without departing from the scope of the invention.

From the foregoing description and accompanying 30 drawings, it will be seen that the instant invention provides an excavating or trenching machine with an improved digging unit particularly adapted for use in hard types of material, such as shale, coral, sandstone and the like, and embodying slicer means which greatly increases 35 the efficiency of the digging unit and helps to alleviate the "pounding" of the digging unit, when operating in such hard material, thereby greatly increasing the service life and useability of the machine.

40 The terms and expressions which have been employed are used as terms of description and not of limitation, and there is no intention in the use of such terms and expressions of excluding any equivalents of any of the features described or shown, or portions thereof, but it is recognized that various modifications are possible 45 within the scope of the invention claimed.

We claim:

1. In a mobile trench excavating machine, having a 50 movable continuous digging unit including a plurality of excavating buckets with rooter teeth mounted on the leading edges of said buckets, the rooter teeth on said buckets being so arranged that the rooter teeth on one bucket are spaced laterally of the rooter teeth on the next following bucket so that substantially the entire transverse width of the trench to be excavated will be engaged 55 by rooter teeth on a predetermined series of buckets, the combination therewith of scarifier blade means mounted on said unit and projecting outwardly therefrom, each of said buckets having a predetermined number of said blade means associated therewith, the blade means associated with a respective bucket being offset laterally with respect to one another and with respect to the rooter teeth on the respective bucket and being generally aligned in a direction longitudinally of said digging unit with the rooter teeth on the next following bucket, said blade 60 means being adapted to score material to be excavated and facilitate its removal from the trench by said digging unit.

2. In a mobile trench excavating machine, a support, 70 a movable continuous digging unit mounted on said support, said digging unit including a plurality of excavating buckets secured to the periphery of said unit and having rooter teeth secured to the leading edges of said buckets and projecting forwardly therefrom, the rooter teeth on said buckets being so arranged that the rooter teeth on one bucket are spaced laterally of the rooter teeth on

the next following bucket so that substantially the entire transverse width of the trench to be excavated will be engaged by the rooter teeth on a predetermined series of buckets, and ripper blades mounted on the exterior periphery of said buckets and projecting outwardly therefrom, said blades being offset laterally on the respective bucket with respect to the associated rooter teeth thereon, and being generally aligned in a direction longitudinally of the digging unit with the rooter teeth on the following bucket.

3. In a mobile excavating machine in accordance with claim 2 wherein said blades on a respective bucket are mounted directly intermediate the associated rooter teeth and adjacent the leading edge of the respective bucket.

4. In a mobile excavating machine in accordance with claim 2 wherein said blades on a respective bucket are mounted rearwardly of the associated rooter teeth and generally adjacent the rearward edge of the respective bucket.

5. In a mobile excavating machine in accordance with claim 2 including means detachably securing said blades to the respective bucket.

6. A cutter blade sub-assembly adapted for mounting as a unit and in transversely extending relation on the exterior of a toothed excavating bucket of a multi-bucket digging unit of a mobile excavating machine, said sub-assembly comprising a strap-like mounting member having an under surface on one side thereof adapted to be disposed in confronting relation with the exterior of the bucket and having an outer surface on the other side thereof, laterally spaced holder members secured to said outer surface, each of said holder members being spaced predetermined amounts laterally of the next adjacent of said holder members, each of said holder members having an outwardly facing socket therein, a scarifier blade element set in each of said sockets, and means extending into said socket and coating between each holder member and the respective blade element for detachably securing the blade elements in their respective sockets, said means being removable from the respective socket to permit removal of the respective blade element while leaving the respective holder member in secured relation on said mounting member.

7. In a cutter blade sub-assembly in accordance with claim 6 wherein certain of said holder members are disposed in staggered relation in a longitudinal direction with respect to other of said holder members.

8. In a mobile trench excavating machine having a movable continuous digging unit including a plurality of excavating buckets with rooter teeth mounted on the leading edges of said buckets, the rooter teeth on said buckets being so arranged that the rooter teeth on one bucket are spaced laterally of the rooter teeth on the next following bucket so that substantially the entire transverse width of the trench to be excavated will be engaged by the rooter teeth on a predetermined series of buckets, the combination therewith of a plurality of scarifier blade sub-assemblies mounted on the exterior of said digging unit, each sub-assembly being associated with a respective one of said buckets, each sub-assembly comprising a mounting member extending transversely of said digging unit and providing an outwardly facing support surface, a plurality of scarifier blade elements secured on said mounting member and extending outwardly from said surface, said blade elements being offset laterally with respect to one another and with respect to the rooter teeth on the respective bucket and being generally aligned in a direction longitudinally of said digging unit with the rooter teeth on the next following bucket.

9. In a mobile trench excavating machine having a

movable continuous digging unit including a plurality of excavating buckets with rooter teeth mounted on the leading edges of said buckets, the rooter teeth on said buckets being so arranged that the rooter teeth on one bucket are spaced laterally of the rooter teeth on the next following bucket so that substantially the entire transverse width of the trench to be excavated will be engaged by the rooter teeth on a predetermined series of buckets, a plurality of scarifier blade sub-assemblies mounted on the exterior of said digging unit, each of said buckets having one of said sub-assemblies mounted thereon, each sub-assembly comprising a mounting member extending transversely of the respective bucket and providing an outwardly facing support surface, a plurality of scarifier blade elements secured on said mounting member and projecting outwardly from said surface, said blade elements being offset laterally with respect to one another and with respect to the rooter teeth on the respective bucket and being generally aligned in a direction longitudinally of said digging unit with the rooter teeth on the next following bucket.

10. A cutter blade sub-assembly in accordance with claim 6 wherein said mounting member is bent into a generally arcuate-like configuration, said outer surface being convex, said holder members being of block-like exterior configuration, and spacer means disposed between the under side of said holder members and the confronting outer surface of said mounting member to support said holder members so that the latter are disposed in vertical planes extending generally parallel to a vertical plane passing through the center of curvature of said mounting member.

11. In a cutter blade sub-assembly in accordance with claim 6 wherein said mounting member is bent into a generally arcuate-like configuration, said outer surface being convex, said holder members being mounted on said outer surface in radially extending relation therefrom.

12. In a mobile trench excavating machine in accordance with claim 2 wherein each of said buckets is of arcuate exterior configuration in transverse vertical section and wherein each of said blades is of generally elongated construction including inner and outer ends, the blades disposed along the side portions of a respective bucket being bent intermediate said inner and outer ends generally transverse of the respective blade, so as to present a bi-planar configuration in front elevation, with the outer portion of each of said bent blades being disposed in a generally vertical plane extending parallel to the longitudinal vertical center plane of the respective bucket.
